(57) **CLAIM**

The ornamental design for gauge mount, as shown and described.

DESCRIPTION

FIG. 1 is a perspective view of a gauge mount, showing my new design;

FIG. 2 is a top plan view thereof;

FIG. 3 is a bottom view thereof;

FIG. 4 is a front elevational view thereof;

FIG. 5 is a rear elevational view thereof; and,

FIG. 6 is a side elevational right side view, the left side elevational view being a mirror image thereof.
